Primary Examiner — Patricia A Palasik*(74) Attorney, Agent, or Firm* — Faegre Drinker Biddle & Reath LLP(57) **CLAIM**

The ornamental design for a cutting tool, as shown and described.

DESCRIPTION

FIG. 1 is a front view of a cutting tool in accordance with an embodiment of the present design;
FIG. 2 is a rear view thereof;
FIG. 3 is a right side view thereof;
FIG. 4 is a left side view thereof;
FIG. 5 is a top view thereof;
FIG. 6 is a bottom view thereof;
FIG. 7 is a first perspective view thereof;
FIG. 8 is a second perspective view thereof; and,
FIG. 9 is a referential view showing the state in use thereof. The broken lines shown in the drawings represent portions of the cutting tool that form no part of the claimed design.

1 Claim, 5 Drawing Sheets(56)
